RECEPTACLE

John Joseph Fitz Gerald, New York, N. Y.

Application August 23, 1937, Serial No. 160,508

6 Claims. (Cl. 232—42)

This invention relates to deposit and collection receptacles and more particularly to receptacles, having means to detachably secure them to supports, and closures provided with latching means actuated upon the deposit of articles in the receptacles.

One example of such a receptacle and its use is a milk bottle-receiving device, adapted to receive and retain the milk bottle within the device until it may be removed upon actuation of certain mechanism.

An important object of the invention is to provide such a receptacle having means to detachably secure it to a support and bolt it there-to in such a manner that it may not be removed by an unauthorized person, means automatically latching the closure of the receptacle upon the deposit of articles therein and a means having the dual functions of unbolting the receptacle from its support and unlatching the closure.

Another important object is to provide a receptacle which may be detachably secured to a portion of a closure structure, such as a door or a door jamb, and cannot be removed therefrom unless the door be open, nor can the closure be unlatched, when it is once latched, unless the same door be open.

Still another important object is to provide a receptacle for milk bottles or the like which may be temporarily attached to a door or door jamb and when removed there will be no conspicuous or objectionable brackets, projections or the like in sight, neither will it be necessary to mutilate the door or door jamb as by cutting openings or removing portions of the door or door jamb.

Another object is to provide a weight-actuated latching means for a receptacle closure, unlatching of the closure being possible, despite this weight, only when the structure, upon which the receptacle is supported, is in a certain position.

Yet another object is to provide a receptacle, having the novel characteristics enumerated, which comprises few and inexpensive parts and parts not apt to get out of order, freeze or break.

Other objects of this invention will be apparent during the course of the following detailed description of the invention, taken in connection with the accompanying drawing forming a part 50 of this specification, and in which drawing:

Figures 1 to 4 are horizontal sections of various closure structures, illustrating the association of the receptacle therewith.

Figure 5 is a front elevation of the receptacle, 55 with its closure open.

Figure 6 is a vertical section of the receptacle.

Figure 7 is a horizontal section of the receptacle and a portion of a closure structure to which it is secured.

Figure 8 is an enlarged fragmentary view of 5 portions of the combined receptacle-securing bolting and unbolting means and means to unlatch the closure of the receptacle.

In the drawing which shows a preferred embodiment of the invention and its application by 10 a minor modification to various closure structures, and wherein similar reference characters designate corresponding parts throughout the several views, the letter A designates the receptacle, the letter B the modification thereof and 15 the letters C, D, E and F various closure structures with which the receptacles A and B are associated.

The receptacle A preferably comprises a box-like housing 10, having paralleling end walls 11 20 and 12, a rear wall 13, joining the end walls, an upper or top wall 14 and a bottom or lower wall 15, both joining the end and rear walls, and a closure 16, taking the place of a front wall and closing the mouth 17 of the housing, all of which 25 define a compartment or chamber 18.

At the forward edge of the end wall 11 there may be a hinge 19 upon which the closure 16 is hung. The end wall 12 carries considerable of the closure latching means, to be later described 30 in detail, and is provided with a vertically-extending slot 20, which is disposed preferably at or close to the rear wall 13. This slot 20 is associated with the receptacle bolting and unbolting and closure unlatching means, later described. 35

Through the rear wall 13 extend preferably two spaced-apart keyhole-like slots 21. The distance across the slots 21 at their rounded edges 23 is greater than the distance across at the paralleling edges 22, with the straight paralleling edges 22 of the slots uppermost and the rounded edges 23 of the slots lowermost. These slots may be disposed upon the longitudinal medial line of the rear wall 13.

A hinge 24 may be provided and secured by 45 any approved means to the inner face of the bottom wall 15, adjacent the end wall 11, so that a false bottom, later described, may be hinged thereto.

The closure 16 may be provided with an out- 50 wardly-extending knob or handle 25.

Means for detachably supporting the housing to a suitable support is provided and preferably comprises a member 26 for each slot 21. These members 26 may comprise a screw threaded por- 55

tion 27, pointed at one end and each having a squared portion 28 at its opposite end. Capping the squared portion 28 is a hemi-spherical head portion 29 provided with a slot to accommodate a screw driver or the like. It should be noted that each squared portion 28 has a width very slightly less than the width of either slot 21 at the straight parallel edges 22 thereof, and a depth slightly more than the thickness of the rear wall 13. The diameter of the head portion 29 should be slightly less than the distance across either slot 21 at its rounded edges 23. This permits the head portions 29 to enter the slots 21 at their rounded edges 23 but not at their parallel edges 22 and when the squared portions 28 are disposed within the narrower parts of the slots 21, the parallel edges 22 will prevent the members 26 from being rotated. Of course, the members 26 are permanently attached to a suitable support, such as a portion of C, D, E or F, later described, by screwing their screw-threaded portions into the support until only the squared and hemi-spherical head portions protrude. However, it is possible, despite the assembly thus far described, to detach the housing 10 from a support to which the means just described is secured after the housing has been hung upon the members 26, as is now apparent. To prevent this, bolting and unbolting means is provided, which means has another function, as will be later described. The dual means, just referred to, comprises an elongated, flat, reciprocating member or slide 30, having a slot 31 at one end, extending toward the other end, and having a width substantially like the width of the narrower parts of the slots 21, or in other words, slightly more than the width of the squared portions 28. In practice, the width of the slot 31 may be greater, just so it is not greater than the length of the slots 21. At the end of the slide 30, opposite the slotted end thereof, is a ring or finger hold 32 secured to the slide 30 as by turning the end thereof over a portion of the finger hold, so that the finger hold 32 may be swung to form various angles with the slide 30. Extending upwardly at an angle, preferably an acute angle, from the upper edge of the slide 30 is an extension or wing portion 33, having a ledge or shoulder portion 34 extending normal to the wing portion 33 and this ledge portion 34 may be upturned at its end nearest the base of the wing, forming a guard portion 35 for a purpose later described. The wing portion 33 may form, with the slide 30, an acute angular recess 36, as shown particularly in Figure 8, so that two edges are provided,—the upper edge 37 of the slide 30 and the lower edge 38 of the wing portion 33, extending upwardly from the edge 37. The slide 30 extends through the slot 20 in the end wall 12. It should be noted that the length of the slot 20 is somewhat less than the distance from the lowermost edge 39 of the slide 30 to the uppermost tip of the wing portion 33, and that the height of the slide 30 is slightly greater than the length of the slot 20. It is therefore apparent that when the slide 30 is in the slot 20 it cannot be wholly withdrawn and that the guard portion 35 covers much of the slot 20 when the slide 30 is pushed in, as will be described. The slide 30 is slidably attached to the rear wall 13 as by two slide guides 40 and 41 disposed to either side of the uppermost slot 21, secured to the rear wall 13, and positioned so that, as the slide 30 is moved inwardly, the slot 31 therein will overlie the extreme upper end

of that slot 21, with the upper edge of the slot 31 and the uppermost edge of the slot 21 substantially in alignment. Preferably formed as a portion of the slide guide 41 which is disposed nearest the end wall 12, is an upwardly extending guide and abutment 42 having a sloping edge 43 adapted to have the sloping edge 38 of the wing portion 33 in abutment therewith when the slide is pushed inwardly, so that a portion of the guide and abutment 42 fills the recess 36. 10

From the foregoing it will be seen that with this slide 30 pushed in, the slide will effectually bolt the housing 10 to its support until the slide 30 is drawn outwardly, so that it will clear the slot 21, whereupon the housing 10 may be raised 15 upwardly until the head portions 29 of the members 26 align with the rounded parts of the slots 21, and by drawing the housing forwardly, it will come away from its support.

The latching means for the receptacle preferably include a vertically reciprocating member 50, slidably secured to the inner face of the end wall 12 as by spaced apart slide guides 51. This member 50 may be provided with two arms 52 and 53,—one extending toward the mouth 17 of the 25 housing 10 and the other arm 53 toward the rear wall 13.

The arm 52, at its free end is provided with a curved or bent extremity 54 which is adapted to engage a curved or bent keeper 55 of resilient material, although possessing considerable strength, extending from and secured to the inner face of the closure 16. The other arm 53 extends to a position so that it may abut, at its free end, the ledge 34, being bent over so as to 35 form a better contact with the ledge 34.

The reciprocating member 50 is urged upwardly by any suitable means such as a contracting coil spring 56 secured, at one end, to the end wall 12 and, at its other end, to a suitable portion of 40 the member 50.

At the lower extremity of the reciprocating member 50, a portion is inturned as at 57 and normally spaced above the bottom wall 15.

Hinged to the bottom wall 15, as by the hinge 45 24, is a false bottom 58 preferably extending over the greater portion of the fixed bottom wall 15 and with its end, opposite its hinged end, resting upon the inturned portion 57 of the member 50. As may be seen in Figure 5, this tilts the 60 false bottom 58.

With the false bottom tilted, as in Figure 5, the arm 52 will be above the keeper 55 when the closure 16 is in a closed position, but when the false bottom 58 is depressed, as by the weight of 55 the bottle of milk, the false bottom 58 will cause the reciprocating member 50 to move downwardly so that the curved extremity 54 of the arm 52 will engage the curved portion of the keeper 55 and thus latch the closure 16. 60

When the reciprocating member 50 is in its lowermost position the free end of the arm 53 will rest upon the lowermost portion of the ledge 34, but it is necessary that the slide 30 be in its pushed-in position, i. e., its position as shown in 65 Figure 5.

With the closure of the housing 10 latched, as described, the only way to unlatch it is to draw out the slide 30 so that the upwardly sloping surface of the ledge 34 will force the arm 53 upwardly and, consequently, the member 50 and arm 52. This will unlatch the closure 16 and the receptacle may be opened to remove the contents. However, it is now apparent that, while unlatching the closure 16, the housing 10 is also 75

being unbolted from its support so that the housing and its contents may be removed from its support, leaving only the inconspicuous protruding ends of the members 26. From this, it will 5 be apparent that the housing 10 may be readily reattached to its support and bolted against removal.

Since the fingerpiece 32 must protrude from the housing 10, and so as to dispense with relatively costly means, such as padlocks, keys, etc., to secure the slide 30 against unauthorized drawing outwardly, a novel association of the receptacle with its support is provided.

With practically all types of supports, but two 15 types of receptacles will be required. One is that just described as A, and the other, B, has the latching means 50, 51, 52, 53, 54 and 56 arranged upon the left hand end wall and the keeper 55 upon the left hand portion of the closure 16, 20 with the slide 30 protruding from the left hand end wall.

The receptacle A may be attached to closure structures, such as C and F, while the receptacle B may be attached to closure structures, such as 25 D and E.

The closure structure C may include a closure, such as a door 60, hinged as at 61 to a door jamb 62 without trim. In this structure, the receptacle A may be attached to the jamb 62 so that the 30 outer face of the wall 12 will face the closed door 60 and be so positioned that the fingerhold 32, when swung normal to the slide 30 will contact or be very close to the face of the door 60.

In the closure structure D, the door 70 is hung 35 upon a hinge 71 carried by a jamb 72 which is provided with a stop 73. It would be impossible to properly secure the receptacle A to the jamb, as in Figure 1, without cutting the stop 73 so, by the employment of the receptacle B, it may be 40 supported upon the door 70, as shown, with the fingerhold 32 in contact with or very close to the stop.

Figure 3 shows the closure structure E, showing an assembly of doors 80, hinge 81, and jamb 82 45 substantially like E, but with the door hung from the other jamb. With this arrangement, the receptacle B may be employed and supported, of course, upon the jamb 82 of the closure structure E.

In Figure 4, the door 90 is hung by a hinge 91 50 upon a jamb 92 having a stop 93 somewhat like that shown in Figure 2. Because of the stop 93, the receptacle A is employed and supported upon the door 90 of the closure structure F.

In each of these four arrangements, it is now 55 obvious that when the receptacles A and V are upon their supports C, D, E or F, the only time the slide 30 may be drawn out is when the doors 60, 70, 80 or 90, as the case may be, are opened.

When the doors are closed, whether the closure 60 16 is open or latched, the receptacles A and B cannot be detached from their supports and when the closure 16 is latched, it cannot be unlatched while the doors 60, 70, 80, or 90, as the case may be, are closed, since a portion of the closure structure, in each case, blocks movement of the slide 30, for in each case, a portion of the closure structure shields the wall of the receptacle A or B from which protrudes the slide 30.

By the term "substantially in contact" where 70 the member 30 is referred to in the claims is meant that the member 30 including its fingerhold 32 is so near or is in contact with a portion of the closure structure that the member 30 cannot be manipulated to draw it outwardly.

From the above, it will be seen that the same means which unbolts the receptacles from their supports also unlatches the closures 16.

Various changes may be made to the form of the invention hereinabove shown and described 5 without departing from the spirit of the invention or the scope of the claims.

What I claim is:

1. In a receptacle of the class described and adapted to be secured to a headed projection, 10 such as a screw, disposed upon a hinged closure structure which, upon opening of the closure thereof, will reveal a portion of said receptacle which is normally shielded by a portion of said closure structure when said closure structure is 15 in a closed position, a housing provided with outer walls and a closure, one of said outer walls being provided with an aperture for receiving said headed projection; latch means for said receptacle closure; and means, mounted for reciprocal movement inwardly and outwardly of the receptacle at said normally shielded portion, for engaging said headed projection, upon said inward movement, and for disengaging said headed projection and releasing said latch means, 20 upon said outward movement.

2. In combination with a closure structure, including a swinging closure portion and a stationary portion normal thereto when said closure is closed, a receptacle including a housing having walls normal to each other and a receptacle closure, means detachably supporting said housing to one of said portions of the closure structure with one of said walls facing the other of said portions and spaced slightly therefrom; a 30 bolt mounted for movement inwardly and outwardly of the receptacle through said one wall, and engaging and disengaging the supporting means upon said inward and outward movements, respectively, said bolt being retained 40 against withdrawal from engagement with the supporting means, when said closure is closed, by substantial contact with said portion last mentioned; and latching means for said receptacle closure.

3. In combination with a closure structure, including a closure portion and a stationary portion normal thereto when said closure is closed, a receptacle including a housing having walls normal to each other and a receptacle closure, 50 means detachably supporting said housing to one of said portions with one of said walls facing the other of said portions and spaced slightly therefrom; means movable into and out of engagement with said supporting means for respectively 55 bolting and unbolting said housing and said closure structure, including a handle for operatively controlling said latter means, disposed between said one wall and said other portion, when the closure is closed, so as to be accessible for manipulation only upon opening of the closure, and latching means for said receptacle closure.

4. In combination with a closure structure, including a closure portion and a stationary portion normal thereto when said closure is closed, a receptacle including a housing having walls normal to each other and a receptacle closure, means detachably supporting said housing to one of said portions with one of said walls facing the other of said portions and spaced slightly therefrom when the closure is closed; latching means for said receptacle closure; and a member selectively engageable with said supporting means to secure the housing to said one portion, and with said latching means to unlatch the same, in 70 75

cluding a handle portion disposed snugly in the said space between said one wall and said other portion, when the closure is closed, so as to be accessible for manipulation only upon opening of the closure.

5. In combination with a support, a receptacle including a housing having outer walls normal to each other, a floor and a closure for said housing; latching means for said closure including a
10 false bottom within said housing and normally disposed above and movable toward the floor thereof, a reciprocating member operatively connected with said false bottom, a latch arm carried by said reciprocating member, a resilient keeper carried by said closure, adapted to cooperate with said latch arm when said false bottom moves towards said floor, a second arm carried by said reciprocating member and extending away from said closure, and resilient means normally urging said reciprocating member upwardly; means extending through one of said walls, detachably supporting said housing to said support, said means including a member secured to said support and having a substantially squared
15 portion and an enlarged portion capping said squared portion, extending into said housing through a wall thereof; means cooperating with said supporting means for selectively bolting said housing to said support, unbolting said housing
20 from said support, and unlatching said closure, including a slide reciprocable into and out of said housing, having a slot with said squared portion extending into said slot and with the edges of said enlarged portion overlying parts of said slide when the latter is in said housing, said slide having a portion adapted to engage and raise said
25 second named arm when said slide is withdrawn to clear said squared portion and said enlarged portion.

6. In combination with a support, a receptacle including a housing having outer walls normal to each other, a floor, and a closure for said housing; latching means for said closure including a false bottom within said housing and normally disposed above and movable towards the floor thereof, a reciprocating member operatively connected with said false bottom, a latch arm carried by said reciprocating member, a resilient keeper carried by said closure, adapted to cooperate with said latch arm when said false bottom moves toward said floor, a second arm carried by said reciprocating member, and resilient means normally urging said reciprocating member upwardly; means extending through one of said walls, detachably supporting said housing to said support, including a member secured to said support having a portion extending through a wall of said housing and protruding into the compartment within said housing, said portion having an enlarged head; means cooperating with said supporting means for selectively bolting said housing to said closure structure, unbolting said housing from said closure structure, and unlatching said closure, including a slide reciprocable into and out of said housing, having a slot with said portion of said last named member extending into said slot and with a portion of said head overlying a portion of said slide when the latter is in said housing, said slide having a sloping portion extending downwardly toward a wall of said housing, with said second arm in contact therewith at the lowermost portion of said sloping portion when said slide is in said housing and said false bottom is closest to said floor, said second named arm being adapted to ride up said sloping portion when said slide is withdrawn from said housing.

JOHN JOSEPH FITZ GERALD.
